Primary Examiner — Ian Simmons*Assistant Examiner* — Yolanda Robinson(57) **CLAIM**

The ornamental design for a clasping device, as shown and described.

DESCRIPTION

FIG. 1 is a front side perspective view of a clasping device, showing my new design;

FIG. 2 is a rear side perspective view of a clasping device thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view; and,

FIG. 8 is a bottom plan view thereof.

1 Claim, 3 Drawing Sheets
